UNITED STATES PATENT OFFICE

97,835

DESIGN FOR HEATER PLUG

George B. Benander, Yalesville, Conn., assignor
to The Monowatt Electric Corporation, a cor-
poration of Connecticut

Application October 16, 1935, Serial No. 59,018

Term of patent 14 years

To all whom it may concern:

Be it known that I, George B. Benander, a citizen of the United States, residing at Yalesville, in the county of New Haven, State of Connecticut, have invented a new, original, and ornamental Design for Heater Plug, of which the following is a specification, reference being had to the accompanying drawing, forming a part thereof.

In the drawing the single figure is a perspective view showing the heater plug which has a wide longitudinal band and narrow transverse ridges at one end. A spring extends at an angle

from one side of the plug through which a cable is adapted to pass and a switch operating handle is located in the top of the plug. The opposite side of the plug is similar to the side shown in the drawing.

I claim:

The ornamental design for heater plug, as shown and described.

In witness whereof, I have hereunto set my hand.

GEORGE B. BENANDER.
